UNITED STATES PATENT OFFICE.

GEORGE HOLT, OF SPICER, MINNESOTA.

OAR-LOCK.

No. 813,896.

Specification of Letters Patent.

Patented Feb. 27, 1906.

Application filed October 9, 1905. Serial No. 281,883.

To all whom it may concern:

Be it known that I, GEORGE HOLT, a citizen of the United States, residing at Spicer, in the county of Kandiyohi and State of Minnesota, have invented certain new and useful Improvements in Oar-Locks; and I do hereby declare the following to be a full, clear, and exact description of the invention, such as will enable others skilled in the art to 10 which it appertains to make and use the same.

My invention has for its especial object to provide an improvement in oar-locks for row-boats; and to this end it consists of the novel 15 devices and combinations of devices herein-after described, and defined in the claims.

The invention is illustrated in the accompanying drawings, wherein like characters indicate like parts throughout the several 20 views.

Figure 1 is a view in side elevation of my improved oar-lock. Fig. 2 is an edge elevation of my improved oar-lock. Fig. 3 is a vertical section taken on the line $x^3 x^3$ of Fig. 1 25 with some parts shown in full and others broken away. Fig. 4 is a vertical section taken on the line $x^4 x^4$ of Fig. 2 with some parts shown in full and others broken away, and Fig. 5 is a horizontal section taken on the 30 line $x^5 x^5$ of Fig. 4.

The numeral 1 indicates the yoke of the improved oar-lock, provided with a stem 2, that is formed with an annular groove 3, below which it is flattened or notched at 4. The 35 lower wall of the groove 3 terminates in cam-surfaces 5, the purpose of which will presently appear. As shown in Fig. 2, the stem 2 of the yoke 1 is bent at an angle to the plane of the yoke 1, the purpose of which will also 40 presently appear. This stem is arranged to work in a socket or sleeve 6, having the extended bearing-plate 7, and is secured to the gunwales of a boat (not shown) in the ordinary or any suitable way. Said stem 6 is also 45 provided with the internal lateral tongue or lock-lug 8.

The normal position of the oar-lock is shown in the drawings, and the inside of the boat (not shown) would be toward the right 50 with respect to Fig. 2. Of course when the oars are in working position they project downward with respect to their outer ends, and by bending the yoke of the oar-lock outward with respect to the boat a much better bearing for the oars is secured. It also 55 provides an arrangement for preventing the

lateral displacement of the oar-lock when the oar is in use. It also prevents the use of the oars in the oar-lock when the said oar-lock is turned at one hundred and eighty degrees to its operative position. The prongs of the yoke of course would project inward with respect to the boat. When the oar-lock is turned at an angle of one hundred and eighty degrees to its operative position, the 60 notch 4 will permit the stem 6 to be passed into said socket 2; but when turned into the operative position the groove 3 receives the tongue or lock-lug 8 and holds the oar-lock against vertical displacement. 70

The purpose of the cam-surfaces 5 is so that the tongue or lock-lug 8 will move readily into the groove 3.

The above-described device is of comparatively small cost, but is efficient for the purposes had in view. 75

What I claim, and desire to secure by Letters Patent of the United States, is as follows:

1. In an oar-lock, the combination with a socket, of a yoke having a stem fitting said socket, said stem being bent at an angle to the plane of said yoke, and means for locking said oar-lock against endwise movements with respect to said socket, when the said oar-lock is in an operative position, substantially as described. 85

2. In an oar-lock, the combination with a socket, of a yoke having a stem fitting said socket, said stem being bent at an angle to the plane of said yoke, means for locking said oar-lock against endwise movement with respect to said socket, when the said oar-lock is turned into an operative position, and arranged to be removed from said socket when the said oar-lock is turned into an inoperative 95 position, substantially as described.

3. In an oar-lock, the combination with a socket, of a yoke having a stem fitting said socket, said stem being bent at an angle to the plane of said yoke, and said stem and said socket having a tongue and groove arranged to interlock, when the oar-lock is turned into an operative position, substantially as described. 100

4. In an oar-lock, the combination with a 105 socket, of a yoke having a stem fitting said socket, said stem being bent at an angle to the plane of said yoke, said stem and said socket having a tongue and groove arranged to interlock, when said oar-lock is turned into an operative position and arranged to permit endwise movement of said oar-lock when 110

the same is turned in an inoperative position, substantially as described.

5. In an oar-lock, the combination with a socket 6 having a tongue 8, of a yoke 1 having a stem 2 fitting said socket 6, said stem 2 being bent at an angle to the plane of said yoke 1 and having an annular groove 3 adapted to receive the tongue 8 of said socket 2 when the oar-lock is in an operative position, 10 and having a notch 4 adapted to clear said

tongue 8, to permit endwise movement of said oar-lock when the same is turned in an inoperative position, substantially as described.

In testimony whereof I affix my signature 15 in presence of two witnesses.

GEORGE HOLT.
